United States Patent

Des. 237,557
Patented Nov. 11, 1975

237,557

APRON

Doris Brosk, 150 E. 69th St.,
New York, N.Y. 10021

Filed Sept. 17, 1973, Ser. No. 397,860

Term of patent 14 years

Int. Cl. D2—02

U.S. Cl. D2—228

The single figure is a front elevational view of an apron showing my new design, the broken line showing of a doll being for purposes of illustration, the back of the apron has the same configuration as the front but without the decorative motif.

I claim:

The ornamental design for an apron, as shown and described.
